UNITED STATES PATENT OFFICE.

DEAN S. HARLEY, OF GEORGETOWN, ONTARIO, CANADA.

PORTABLE FIRE-ESCAPE.

1,264,179.

Specification of Letters Patent. Patented Apr. 30, 1918.

Application filed January 31, 1917. Serial No. 145,753.

To all whom it may concern:

Be it known that I, DEAN S. HARLEY, of the town of Georgetown, in the county of Halton, Province of Ontario, Canada, have 5 invented certain new and useful Improvements in Portable Fire-Escapes, of which the following is a specification.

This invention relates to fire escapes of the type in which a belt is connected to a 10 friction device slideable on a suspended web or rope, and my object is to devise a simple and reliable escape of this type which is readily reversible by simply turning the suspending web end for end after the apparatus has been used and the friction device is at the lower end, and to provide controlling means operable by a person using the device which will make it unnecessary for him to grasp the suspended web. 15

20 I attain my object by means of the construction hereinafter described and illustrated in the accompanying drawings in which—

25 Figure 1 is a front elevation of my device ready for use;

Fig. 2 a side elevation of the same; and

Fig. 3 a perspective view of the friction device on an enlarged scale.

30 In the drawings like numerals of reference indicate corresponding parts in the different figures.

35 The essential elements of the device are a suspended web 1, a friction device 2 adapted to run on the web, and the belt or other support 3 connected to the friction device, the apparatus being used by connecting the web 1 at one end to the building from which the descent is to be made, the person descending sitting in the belt 3 or having 40 it passed around his body.

45 The web 1 is provided at one end with a suitable hook adapted to engage a suitable eye 5 secured to part of the building. It is evident also that a loop could be formed in the web by engaging the hook 4 with the web so as to form a loop in the web which could be passed around a bed post or other part sufficiently heavy to give 50 secure anchorage for the upper end of the web.

55 The friction device 2 is formed as a rectangular frame 6 crossed by five transverse bars 7. At each side of the frame a slot 8 is formed extending substantially the full length of the frame. The whole is formed

integrally of metal and is preferably a malleable iron casting. The web is woven through the bars as shown, passing under the center bar and over the adjacent bars at each side, thence under the end bars. 60 The slots 8 form means of connection for the belt 3, the ends of which are provided with means, such as snap hooks 9, by means of which they may be engaged with the slots. 65

The device is used as follows. The upper end of the web is suitably connected with the building as already described. The belt is passed around the user, who then entrusts his weight to the device, controlling 70 the rate of descent by applying tension to the web below the friction device. In the case of a helpless person, such tension may be applied by a person on the ground gripping the lower end of the web. 75

If a second person is to descend from the same place, the person above disconnects the web at the upper end, hauls up the device and connects the other end of the web with the building. The friction device is thus 80 again brought to what is the upper end of the web, the hooks 9 sliding to the other end of the slots and thus automatically reversing their position. The second person then descends in the same manner as the 85 first.

As many persons would find difficulty in controlling their descent by grasping the web and might burn their hands by the friction of the same, I prefer to employ a brake 90 member and operating means therefor which do not move relative to the friction device. For this purpose I form on the rectangular frame 6 lugs 10 carrying a pin 11, on which is journaled a brake 12. This 95 brake is provided with oppositely extending brake arms 13, one of which is adapted to coöperate with the cross bar next adjacent the center bar at one side thereof and the other with the cross bar next adjacent the 100 center bar at the other side thereof. Intermediate the brake arms is the operating arm 14, loop shaped as shown for connection with a strip of webbing 15, preferably formed as a loop in which the hand may 105 be inserted. By pulling down on this loop 15, the web 1 may be gripped between the lower brake arm 13 and the bar with which it coöperates. When the device is reversed, the other brake arm 13 and coöperating 110

cross bar are in position to coöperate and produce the desired braking friction on the web.

From the above description it will be seen that I have devised a fire escape which will satisfactorily attain the objects of my invention as set out in the preamble to this specification.

What I claim as my invention is:—

- 10 A one-piece friction device for portable fire escapes of the kind described shaped to form a central rectangular frame crossed by five cross bars and at each side of the central frame a slot extending substantially the full length of the frame, and a bearing
- 15

lug at the inner side of each slot in line with the center bar in combination with a one-piece brake fulcrumed on said lugs and comprising three pairs of radial arms having their ends connected by parallel cross bars, the opposite brake cross bars being adapted to coöperate with the cross bars of the friction device next adjacent the center, and the intermediate brake cross bar serving for the attachment of an operating device.

Signed at the village of Georgetown, in the county of Halton and Province of Ontario this 23rd day of January, 1917.

DEAN S. HARLEY.
